UNITED STATES PATENT OFFICE.

OLAF S. STROM, OF LOS ANGELES, CALIFORNIA, ASSIGNOR TO PITTSBURGH VALVE AND FITTINGS COMPANY, OF BARBERTON, OHIO, A CORPORATION OF NEW JERSEY.

DESIGN FOR A BRACKET LIGHTING FIXTURE.

Application filed October 31, 1928. Serial No. 28,701. Term of patent 7 years.

To all whom it may concern:

Be it known that I, OLAF S. STROM, a citizen of the United States, residing at Los Angeles, in the county of Los Angeles and State of California, have invented a new, original, and ornamental Design for Bracket Lighting Fixtures, of which the following is a specification, reference being had to the accompanying drawing, forming a part thereof.

Figure 1 is a side view of my complete design and Figure 2 is a fragmentary front view showing the wall plate forming a part of the design illustrated in Figure 1.

I claim:

The ornamental design for a bracket lighting fixture as shown.

OLAF S. STROM.
